UNITED STATES PATENT OFFICE.

MAX SCHEUER, OF NEW YORK, N. Y.

DESIGN FOR A PURSE OR POCKET-BOOK.

SPECIFICATION forming part of Design No. 21,974, dated November 8, 1892.

Application filed October 10, 1892. Serial No. 448,459. Term of patent 7 years.

To all whom it may concern:

Be it known that I, MAX SCHEUER, a citizen of the United States, residing at New York city, New York, have invented and produced a new and original Design for Purses or Pocket-Books, of which the following is a specification, reference being had to the accompanying drawing, showing a perspective view of a purse provided with my design.

The leading feature of my design consists of a pocket-book or purse upon the top plate of which is represented a monument surrounded by a railing and a landscape scenery consisting of hills and trees.

a represents the top plate of the purse b, 15 surrounded by a raised rim a' on three sides. On the fourth side the top plate is provided with a twisted border c. Within the rim a' there is represented a monument d, surrounded by railing e, and also a landscape 20 scenery consisting of the hills f and trees g.

What I claim is—

The design for a pocket-book or purse, as herein described and shown.

MAX SCHEUER.
